UNITED STATES PATENT OFFICE.

EDWARD NELSAN WHITE, OF GUANTANAMO, CUBA, ASSIGNOR OF ONE-HALF TO
WILLIAM HENEAGE RAMSAY, OF GUANTANAMO, CUBA.

PHOTOGRAPHIC-PRINTING FRAME.

1,319,442.

Specification of Letters Patent.

Patented Oct. 21, 1919.

Application filed February 8, 1919. Serial No. 275,795.

To all whom it may concern:

Be it known that I, EDWARD NELSAN WHITE, a citizen of the United States, residing at Guantanamo, Cuba, have invented 5 certain new and useful Improvements in Photographic-Printing Frames; and I do hereby declare the following to be a full, clear, and exact description of the invention, such as will enable others skilled in the art 10 to which it appertains to make and use the same.

This invention relates to photographic printing frames and is directed to the provision of a frame of an improved construction whereby borders of various widths and 15 shapes may be produced on photographic prints, whether obtained from films or from dry plates, irrespective of the size and shape of the film or plate.

20 The invention further involves the provision of an improved device for pressing the sensitized paper against the negative, whether film or plate, so as to hold it in place during the printing operation, this 25 pressing device forming part of the back of the frame and being readily removable therefrom and replaceable by a device of different size or shape to correspond with the printing opening in the mask, which latter is likewise 30 made removable for the same purpose.

In employing the invention in the form at present considered preferable, I provide a mask in the nature of a plate or sheet of suitable material, which is adapted to rest 35 against the usual glass plate in the frame, and which has formed in it at one end an opening for the reception of the negative and corresponding in size and shape thereto, this opening being edged with a strip of 40 opaque material which projects beyond its margin and is utilized to form the desired border on the print. The back of the frame is constructed to receive the presser device above referred to, this device being in the 45 form of a removable panel carrying upon its outer face a pad which generally conforms in size and shape to the printing opening in the mask, and which when the back is in the closed position, bears directly 50 against the paper and thus holds it yieldingly against the negative. The mask and the panel and pad constitute what may be regarded as a printing set, and any number of these sets may be employed in connection 55 with a single frame or holder, so that the

latter may be utilized to obtain prints from films and plates whose dimensions vary within an appreciable range, the interchange of sets being easily effected.

The drawings illustrate what is regarded as the preferred form in which to embody the invention, but it is to be understood that no limitation to the precise structural features illustrated is contemplated, since modifications and changes may well be made 60 within the scope of the invention as subsequently claimed.

In said drawings:—

Figure 1 is a rear elevation of the improved printing frame, showing the member or section of the back which carries the presser device in open position and also showing a film partly removed from the frame;

Fig. 2 is a longitudinal sectional view of the frame in closed position;

Figs. 3 and 4 are perspective views of the mask and presser device, respectively, a portion of Fig. 3 being broken away adjacent the printing opening to disclose more 80 clearly the arrangement of the opaque strip for producing the border; and

Fig. 5 is a perspective view of the presser device and its carrier.

Referring more particularly to the drawing, the frame consists, generally, of a main member or frame proper 1, and a rear member of back 2, as is usual in devices of this character, the back consisting, in turn, of two sections 3 and 4 which are hinged together along their adjacent edges and are retained in place in closed position in the main member or frame proper by suitable spring clips 5, the ends of which are designed for engagement by catches 6 fastened to the rear face of the frame. The frame is also provided with the usual plate of transparent glass indicated at 7, all of the parts just specified being in the main or conventional form and utilizable in the ordinary 90 manner.

The printing set, which presents the essential features of the invention, consists, as previously stated, of a mask, and a device co-operating therewith for pressing the paper 105 against the negative during printing. The former of the two parts indicated consists of a plate or sheet 8 of heavy cardboard or the like, in one end of which is cut an opening 9 having the exact size and shape of the 110

negative from which the prints are to be made. The front face of the mask, that is, the face next the glass plate 7, has pasted on it a strip of black paper or other opaque material, indicated at 10, this strip extending along the marginal edges of the opening 9 and projecting beyond those edges inwardly of or over the opening to the extent necessary to form a blank border of the required width upon the print; it being understood, of course, that the negative will fit in the opening 9, and that the portion of the opaque strip which projects out into the opening will overlie the sensitized paper and prevent printing on the latter to that extent. With the arrangement above described, the border will be formed along three edges only of the print; the border along the remaining or fourth edge may be produced by means of an opaque strip 11 similar to the strip 10, which bridges the outer end of the opening 9 and may be secured either to the mask or to the inner face of the glass plate 7, as may be preferred.

25. The other element of the printing set preferably consists of a pad 12 of the required thickness and of a shape conforming to that of the mask opening 9, this pad being secured to a panel 13 which, in turn, is slidably mounted in the section 3 of the back 2. The section 3, as shown in Fig. 5, may be provided with a suitable slideway 14, which is in the inner face of the section 3, and which has its opposite edge walls undercut 35 to form guide grooves 15. The outer face of the pad 12 is preferably furnished with a covering of felt or similar yielding material, and since the pad conforms in size and shape with the mask opening 9, a change in the 40 size of the film from which the print is to be made will entail the removal of both the mask and the pad, and the substitution therefor of a new printing set in which the mask opening and pad are of the proper size. However, the mask may be readily withdrawn from the frame and replaced by a new one after the back 2 has been detached, and the panel 13 which carries the pad can be easily slid out of its seat in the 50 back member or section 3, so that the operation of changing from one printing set to another requires but little time.

I claim as my invention:

1. The combination with a printing frame 55 comprising a main member and a back removably fitting therein, of a mask removably fitting in the main member and having a printing opening, and a pad connected to the back in position to fit in said opening 60 when the back is in place.

2. A mask for printing frames having a printing opening which is adapted to re-

ceive a negative and which conforms in size and shape to the negative so as to permit said negative to fit therein and be held in 65 place by the edges thereof during printing.

3. A mask for printing frames having an opening to receive a negative during printing, said opening conforming in size and shape to the negative, and a projecting strip 70 of opaque material attached to the front face of the mask and extending along the marginal edge of the opening in position to overlie the negative so as to produce a blank border on the print.

4. The combination with a printing frame comprising a main member, a glass plate fitting therein and a detachable back, of a mask removably arranged within the main member against said plate and having a 80 printing opening at one end thereof to receive a negative during printing, a strip of opaque material attached to the mask along the edge of said opening and extending across the latter in position to overlie the 85 negative so as to produce a blank border along a portion of the margin of the print, and opaque material on said plate in position to bridge the open end of said opening and thereby produce a blank border along 90 the remainder of the margin of the print.

5. The combination with a printing frame comprising a main member and a detachable back therefor embodying a pair of hinged sections, of a mask removably fitting in the 95 main member and having a printing opening, and a pad removably connected to the inner face of one of said back sections in position to fit in said opening when the back is in place.

6. The combination with a printing frame comprising a main member and a detachable back therefor embodying a pair of hinged sections, of a mask removably fitting in the main member and having a printing opening, a panel slidably connected to the inner face of the back section which is adapted to cover said opening, and a pad carried by the panel in position to fit in said opening.

7. The combination with a printing frame 110 comprising a main member and a detachable back therefor, of a mask removably fitting in the main member and having a printing opening to receive a negative during printing, said opening having a projecting strip 115 of opaque material extending along its marginal edge in position to overlie the negative so as to produce a blank border on the print, and a pad connected to the back in position to fit in said opening when the 120 back is in place.

In testimony whereof I affix my signature.

EDWARD NELSON WHITE.
